FIG. 3.

Patented May 18, 1926.

1,585,115

UNITED STATES PATENT OFFICE.

AMOS B. RUMSEY, OF EELCOIT, WISCONSIN, ASSIGNOR TO COVINGTON MACHINE COMPANY, INC., OF COVINGTON, VIRGINIA, A CORPORATION OF VIRGINIA.

CLINKER EXTRACTOR.

Application filed September 3, 1925. Serial No. 54,209.

This invention relates to machines for extracting clinker or other material from furnaces, ovens, retorts, etc., and comprises all improvements over the prior art which are disclosed in this application. One object is to so support the frame of the machine that the shovel side of the machine may be brought up close to the furnace opening, while at the same time the supporting wheels on the shovel side of the machine are placed sufficiently far back from the furnace opening so that the supporting rail for these wheels can be so placed as not to substantially interfere with the clinker falling into the hopper mouth. Also by thus having the shovel side of the main frame relatively near the mouth opening, a shorter ram bar can be used to reach the back of the furnace. This not only makes for less spring and whipping action in the ram bar in operation, but also permits of the ram bar being short enough to clear the posts at the rear of the ram bar, thus enabling the operator to more effectively keep his mind on his work of extracting clinker, and hence enable him to extract clinker at a faster rate.

The above and other objects which will hereinafter appear, are attained by new and useful improvements as disclosed in this application. To enable others skilled in the art to fully understand the essential features of the improvements, drawings have been annexed as a part of this disclosure.

Fig. 1 is a vertical section of a zinc oxide furnace and the adjacent yard construction with the clinker extractor shown in end view.

Fig. 2 is a plan view of the clinker extractor.

Fig. 3 is a side elevation of the clinker extractor.

1 represents a zinc oxide furnace having loose grate bars 2 extending from the front to the rear of the furnace. Opening 3 has a bottom 4 upon which is secured a filler plate 5 by means of countersunk screws 6, the filler plate being of substantially the same thickness as the grate bars 2. The outer edge of the filler plate 5 is preferably beveled at 7 to aid shovel 16 in properly entering opening 3.

Outside of the furnace is a yard construction comprising a floor 8, posts 9 and hopper mouth 10. Mounted on floor 8 are rails 11, 12 secured in place by any suitable means,

Rail 12 projects over the hopper mouth 10 only to a slight extent and therefore does not substantially interfere with the clinker falling into the hopper mouth from opening 3. But if rail 12 is thus placed, and if the clinker extractor 13 is provided with a normal frame and wheel construction, the extractor frame 14 must be so far from the furnace opening 3, that for practical construction and operation, ram bar 15 must be of exceptional length to reach the extreme back of the furnace. This extra length of ram bar 15 would result in more spring and whipping action of the ram bar while the shovel 16 is working near the back of the furnace, and when the shovel 16 were retracted to position shown in Fig. 1, the longer ram bar would strike posts 9.

The extractor 13 comprises a frame 14 mounted upon wheels 17, 18, 19, 20. Wheels 17, 18 are keyed to axles 21, 22 which are journalled in opposite sides of frame 14 and carry collars 23, 24 which cooperate with wheels 17, 18 to retain the axles from substantial longitudinal movement. Wheel 19 is smaller than wheel 17 and is located beneath frame 14 and keyed on axles 25 carried by two part bearings 26, 27 bolted to frame 14. Wheel 20 is the same size as wheel 19 and is located partly beneath frame 14 and keyed on axle 28 carried by two-part bearings 29, 30 bolted to frame 14.

Formed on the top of the frame 14 is a ring track 31 on which travels the supporting rollers 32 of ram carriage 33 which is swiveled on vertical shaft 34. Electric motor 35 is fastened to frame 14 and acts through gearing 36, 37, 38, 39, universal joint 40, screw 41 and nut 42 pivoted to ram carriage 33, to swing the ram carriage in either direction about shaft 34 as a pivot, by causing the motor 35 to rotate in either direction by known electric control devices.

Keyed on shaft 34 is a pinion 43 meshing with rack 44 on ram bar 15 carrying shovel 16. Also keyed on shaft 34 below the top of the frame 14 is a large bevel gear 45 meshing with bevel pinion 46 which freely turns on shaft 47 and has clutch teeth 48. Splined on shaft 47 is a clutch 49 having clutch teeth on its opposite sides and being adapted to be slid in opposite directions on shaft 47 by means of clutch lever 50 swinging a bar 51 which passes through clutch 49 and fits loosely in a socket

52 in frame 14. Pinion 53 is free on shaft 47 and has clutch teeth 54. Electric motor 55 rotates shaft 47 through gears 56, 57. By moving the clutch 49 toward pinion 53, 5 the clutch slides under and raises the lifting bar 58 projecting from brake dog 59, thus lifting brake dog 59 out of locking engagement with pinion 53. By moving clutch 49 further until its clutch teeth engage clutch teeth 54, pinion 53 is rotated, and hence gear 60 keyed on shaft 61 is rotated and through bevel pinions 62, 63, 10 on opposite ends of shaft 61, bevel gears 64, 65, are rotated and rotate axles 21, 22, 15 and consequently wheels 17, 18, to move the machine along the track. Motion in either direction is obtained by reversing motor 55 in a well known manner. By shifting clutch 49 in the opposite direction, lifting bar 58 is released to permit brake dog 59 to fall into engagement with the teeth of pinion 53 to hold the machine in position where it is placed. By shifting the clutch 20 still further, it engages clutch teeth 48 on bevel pinion 46 and through bevel gear 45, shaft 34 and pinion 43 and rack 44, operates ram bar 15 laterally of the machine. Reciprocating movement of ram bar 15 is obtained by reversing motor 55. The ram 25 bar is held and guided by rollers in a manner broadly similar to that disclosed in Patent 768,067 to McConnell.

Thus by the mechanism described, the machine can be shifted along a track to any 30 position desired. The ram carriage can also be swiveled about shaft 34 to any angle de-

sired, and the shovel can be reciprocated into and out of a furnace opening.

Wheels 17, 18 operate to shift the machine along the track and to support one side of the machine. Wheels 19, 20 support the opposite or shovel side of the machine, but are not driving wheels.

All changes which properly come within the spirit and range of equivalency of the 45 following claims are intended to be embraced within the scope of the claims.

I claim:

1. In a machine for extracting clinker and the like, a frame, a shovel mounted at 50 one side of the frame and adapted to be reciprocated transversely of said frame, a pair of axles extending transversely of and mounted in the opposite sides of, said frame, a wheel mounted on each axle at the side 55 of the frame remote from the shovel, a second pair of axles mounted on the frame, a wheel mounted on each of said second pair of axles having a portion within the line passing longitudinally of the frame 60 along the outside of the shovel side frame mountings of said first pair of axles.

2. The machine set forth in claim 1, in which the wheels on said second pair of axles are mounted beneath the shovel side 65 of said frame.

3. The machine set forth in claim 1, in which the axles of said second pair of axles are farther apart from each other, than the 70 distance between the axles of said first pair of axles.

AMOS B. RUMSEY.
